UNITED STATES PATENT OFFICE.

JOHN P. EUSTIS, OF NEWTONVILLE, MASSACHUSETTS.

DESIGN FOR A DRAINER FOR DISHES.

SPECIFICATION forming part of Design No. 35,670, dated February 4, 1902.

Application filed November 29, 1901. Serial No. 84,144. Term of patent 7 years.

To all whom it may concern:

Be it known that I, JOHN P. EUSTIS, a citizen of the United States, residing at Newtonville, in the county of Middlesex and State of Massachusetts, have invented and produced a certain new and original Design for a Drainer for Dishes, of which the following is a specification, reference being had therein to the accompanying drawings.

Figure 1 is a plan view of a drainer, showing my new design. Fig. 2 is a sectional view taken at line 2 2 of Fig. 1, and Fig. 3 is a sectional view taken at line 3 3 of Fig. 1.

As shown in the drawings, the leading or material feature of my design consists of the exterior outwardly and downwardly extending flange A, which extends continuously around and forms the brim of the oblong drainer A', the bottom of which is formed with

the perforations a, and the corners a' of which are rounded. Flange A extends downwardly only part way to the bottom of the drainer.

Having described my invention, what I claim as new, and desire to secure by Letters Patent, is—

The design for a drainer for dishes, as herein shown and described the drainer being oblong, and having a perforated bottom, rounded corners, and exterior flange which extends downwardly part way toward the bottom of the drainer, and continuously around the drainer.

In testimony whereof I affix my signature in presence of two witnesses.

JOHN P. EUSTIS.
